UNITED STATES PATENT OFFICE.

EDMOND T. PATNAUDE, OF PROVIDENCE, RHODE ISLAND, ASSIGNOR, BY MESNE ASSIGNMENTS, TO CLARK LIGHTER CO., INC., OF NORTH ATTLEBORO, MASSACHUSETTS, A CORPORATION OF MARYLAND.

POCKET CIGAR LIGHTER.

Application filed November 26, 1927. Serial No. 235,811.

This invention relates in general to improvements in pocket cigar lighters. 55

One of the objects of this invention is the provision of a new form of spark wheel and means for operating the same in pocket cigar 5

lighters. 10 A further object of this invention is the provision of a novel form of construction in pocket cigar lighters in which the spark wheel is pivoted wholly or in part on the end of the flint tube. A further object of this 15 invention is the provision of a thumb wheel for operating the spark wheel of the pocket cigar lighter by means of a natural movement of the thumb.

These and other objects as will appear from the following disclosure result from this invention.

Referring to the drawings in which the 20 same reference numerals will be used in the several views to indicate the same or similar parts,

Figure 1 is a side view of the lighter of this invention showing the method of holding it in the hand and the method of operating it.

Figure 2 is a top plan view of the lighter.

Figure 3 is a longitudinal cross sectional view through the flint tube, spark wheel and thumb wheel.

Figure 4 is a similar cross-sectional view of a modified form, and

Figure 5 is a cross-sectional view of a still further modification not employing the thumb wheel.

The usual forms of cigar or cigarette lighters as they are now known employ some form of rotatable spark wheel, and in some lighters now on the market, the spark wheel is operated by means of a thumb wheel. So far as I am aware all lighters of these types have the spark or spark and thumb wheels mounted on a vertical axis, so as to rotate in a horizontal plane. When the lighters are constructed in this manner, the operating movement of the thumb of the user is in a direction at an angle to the axis of rotation of the spark wheel or spark and thumb wheels or an angularity is assumed between the phalanges of the thumb. Thus greater energy is required to produce the same amount of sparks by means of these lighters than in the device hereinafter set

forth wherein the thumb need not be bent at all for purposes of proper operation.

The present invention involves a lighter in which the spark wheel or the spark and thumb wheel lie in a plane in which the direction of movement of the user's thumb lies.

For a better understanding of the invention, reference is made to the drawings in which at 1 is shown the usual fluid container having a threaded plug 2 adapted to be removed when the container is to be filled. 65 On the top of the container is mounted a horizontal flint tube 3 in the vertical standard 4. A spring is mounted within this tube and is pressed by means of the threaded screw 5 to force the flint 11 against the spark wheel. The flint tube 3 is enlarged as at 6 in one form of the invention. The large end lies in a plane at an angle with the horizontal or the top of the fluid container. The thumb wheel for operating the spark 70 wheel is shown at 7, and it likewise lies in a plane at an angle with the horizontal for the top of the fluid container. On the standard 8 (Figure 2) is pivotally mounted the snuffer arm 9, which cooperates with the 75 snuffer arm 10 for snuffing out the light. 80

As is well known with these devices, the interior of the container is provided with an absorbent material, such as cotton, and the wick carries the fuel on the inside of the 85 container to the outside through the wick tube.

Referring to Figures 3, 4, and 5, the interior of the flint tube 3 is shown provided with the spring 10 to force the flint 11 90 against the spark wheel 13. In the forms shown in Figures 3 and 4, the spark wheel is rotated by means of the thumb wheel 7. In the arrangement of Figure 3, the spark wheel and the thumb wheel are arranged for 95 simultaneous rotation about the pin 12 which is mounted in the enlarged end 6 of the flint tube and in the short standard 17 secured to the top of the fluid container. In the arrangement of Figure 4, a short pin 14 is 100 riveted in the enlarged end 6 of the flint tube, and the spark wheel 13 and the thumb wheel 17 and held thereon for rotation by means of the machine screw 15. In the arrangement of Figure 5, there is no thumb 105 wheel provided, but the spark wheel 13 is

mounted for rotation on the pin 15, in the end of the flint tube 3.

The operation of this device will be readily apparent from Figure 1 of the disclosure, 5 where the thumb of the holder swings in an arc which lies in general in the plane of the thumb wheel 7. Since this is the natural direction of movement of the thumb in operating one of these devices, it is apparent 10 that the particular arrangement devised is very easily operated.

I am well aware that many changes in the details of construction and relative arrangement of parts will occur to those skilled in 15 the art, and I do not therefore, desire to be limited to the disclosure in the drawings, which has been given in the illustrative sense, but rather to the invention as it is defined in the appended claims.

20 What I seek to secure by United States Letters Patent is:—

1. The combination comprising a flint tube

for a pocket lighter and a spark wheel and thumb wheel both mounted for rotation on the end of the flint tube, the axis of rotation of the thumb wheel being at an oblique angle to the axis of the flint tube. 25

2. In a pocket lighter the combination with a fuel container and a flint tube of a spark wheel and a thumb wheel arranged 30 for rotation in planes at an oblique angle with the axis of the flint tube.

3. A combination as described for use on cigarette lighters comprising a flint tube having an enlarged end, a spark wheel in said 35 enlarged head, and a thumb wheel, said spark wheel and thumb wheel being journaled for conjoint rotation on said flint tube and in planes at an oblique angle with the 40 axis of the flint tube.

In testimony whereof I have hereunto set my hand on this 22nd day of November, A. D. 1927.

EDMOND T. PATNAUDE.
